UNITED STATES PATENT OFFICE

2,509,480

COIN ACTUATED CLOCKLESS PARKING METER

Henry Purl Compton, Abilene, Tex.

Application December 16, 1948, Serial No. 65,560

3. Claims. (Cl. 232—1)

1

This invention relates to parking meters.

An object of this invention is to provide a receiver for mounting on a curb for receiving coins deposited by motorists, the receiver being provided with means whereby an attendant having a key may determine whether a coin has been deposited and upon removal of the key the coin will drop into the collector.

In certain towns and cities, it is desirable that motorists be charged for parking vehicles at the curb, and that means be provided which may be produced at small cost and which will produce an income at a minimum operating cost.

While in many areas employing parking meters it is desirable or necessary to limit the parking time of a vehicle to a stated period, as for example, an hour or half hour in congested urban localities, in other areas the converse is true. For example, in suburban or village areas a large number of vehicles may park in a specific locality, as in front of the post office or various stores in the course of an hour. If conventional timed meters are used the first user to park deposits a coin actuating the meter for a specified time and all subsequent users during such time may enjoy the privilege imparted by the first coin.

An important object of this invention is therefore to overcome the above difficulty by providing a parking meter in which each user of the space must deposit a coin regardless of the length of time the space may have been occupied by his predecessor.

With the above and other objects in view, my invention consists in the arrangement, combination and details of construction disclosed in the drawings and specification, and then more particularly pointed out in the appended claims.

In the drawings,

Figure 1 is a detail front elevation of a parking meter constructed according to an embodiment of my invention.

Figure 2 is a fragmentary rear elevation of the upper portion of the meter with the closure in open position.

Figure 3 is a sectional view taken on the line 3—3 of Figure 2.

Figure 4 is a fragmentary sectional view taken on the line 4—4 of Figure 2.

Figure 5 is a fragmentary sectional view taken on the line 5—5 of Figure 2.

Figure 6 is a fragmentary sectional view taken on the line 6—6 of Figure 2.

Referring to the drawings, the numeral 10 designates generally an upright housing formed of a body 11 having a front wall 12, right angularly

2

disposed side walls 13, and a top wall 14. The side walls 13 converge toward each other at their lower portions as shown in Figure 1, and an ear 15 is formed at the lower portion of the housing 10 on the opposite sides of which a pair of ears 16 carried by a closure 17, which comprises the rear wall of the housing, is adapted to be pivotally mounted on a pivot 18.

The closure in the present instance is stationary and may be secured to an upright support by any suitable fastening means, while the housing is movable about the pivot 18 for the purpose of removing coins deposited therein in a manner to be hereinafter described.

The housing member 11 is adapted to be locked relative to the closure 17, by means of a bolt 19 carried by a key operated shaft 20, and the bolt 19 is adapted to engage in a keeper groove 21 carried by a keeper lug 22 which is fixed to or formed integral with the closure 17. The top wall 14 is formed with a coin slot 23 and a channel-shaped coin guiding chute 24 extends downwardly and inwardly from the slot 23.

The chute 24 includes a plate 25 and an offset flange 26 which is adapted to be secured by a single fastening member 27 to a lug or projection 28 which is carried by the adjacent side wall 13. The wall 12 of the housing 11 is formed with an elongated rib 29 which is curved downwardly and inwardly at its lower portion, as shown in dotted lines in Figure 2, and forms with the lower portion of the chute 25 a coin guiding means for guiding the released coin into an offset receiver or chamber 31 which is formed in the lower portion of the housing 11.

In order to provide a means whereby the coin which is inserted into the slot 23 will be held against dropping into the receiver 31, I have provided a coin holding lug 32 which is carried by a plate 33 pivotally mounted on a pivot member 34. The pivot member 34 extends through the inner wall of the chute 24 so that it will form a part of the chute for assembly purposes. The holding lug 32 extends through an arcuate slot 35 formed in the lower portion of the chute 24 and when the lug 32 is in holding position, this lug will project into the chute 24. When the lug 32 is in released position, this lug is adapted to be swung laterally into a slot 36 which is formed in the upper portion of the rib 29 (see Fig. 2).

The front wall 12 of the housing 11 is formed with a circular window 37 which is disposed below the horizontal plane of the lug 32 so that when the lug 32 is in coin holding position, the coin engaged thereby will not be visible through the

window 37. The lug 32 with the plate 33 is adapted to be swung laterally to released position by means of a releasing finger 38 which is carried by a key operated shaft 39. The shaft 39 extends through the front wall 12 of the housing 11 and the finger 38 is disposed loosely between a pair of spaced apart lugs 40 and 41 which are struck or bent inwardly from the plate 33 below the lug 32.

A second coin holding lug 42 is bent forwardly from the plate 33 below the lug 32 and the window 37, and is laterally offset from the lug 32 so that when the plate 33 is swung to coin releasing position, lug 42 will be disposed within the chute 24 and below the window 37. At this time the coin which was held by the upper or first lug 32 will drop downwardly and engage the second or lower lug 42. The coin at this time will be exposed through the window 37.

The shaft 39 with its key mechanism is then rotated to a key releasing position which also swings the plate 33 to a coin depositing position wherein the lower lug 42 is moved out of the path of the coin and out of coin chute 24, permitting the coin to drop downwardly into the chamber or receiver 31. In the operation of the device it is contemplated that an attendant or police officer be provided with a key for rotating shaft 39, and that such individual inspect all meters at regular or irregular intervals. Upon rotation of shaft 39 if a coin is exposed in window 37 the motorist is considered to be parked legally. If no coin is exposed the parking is illegal. Since each coin may be exposed only once at the window upon rotation of the shaft it will be understood that the duration of even a voluntarily unlawful parking may be determined by the interval between visits of the attendant. Since no coin will be visible except to the attendant when using the key one proposing to park will have no way of knowing whether or not a coin is in the meter other than by depositing one.

In view of the fact that these meters eliminate the spring operated flag mechanism, the meter can be produced at small cost so that a substantial number of these meters or collectors may be placed at predetermined positions either along the curb or on a parking lot.

I do not mean to confine myself to the exact details of construction herein disclosed, but claim all variations falling within the purview of the appended claims.

What I claim is:

1. A parking meter comprising a housing having a coin slot, a coin guiding chute in said housing extending from said slot, said housing having a window between the ends of said chute, a

coin holding member pivotally carried by said housing projecting into said slot adjacent said window for holding an inserted coin against movement past said window, a second coin holding member fixed relative to said first coin holding member positioned below said window whereby upon movement of said first coin holding member to released position the coin will be held in a position confronting said window, and a common operating means for said coin holding members.

2. A parking meter comprising a housing having a coin slot, a coin guiding chute in said housing extending downwardly from said slot, said housing having a window between the ends of said chute, a plate pivotally carried by said housing, a coin holding lug carried by said plate and projecting into said slot for holding a coin above said window, a second coin holding lug carried by said plate disposed below said window and positioned laterally of said first lug, said second lug being disposed in released position when said first lug is in operative position and adapted to be disposed in operative position within said chute when said first lug is in released position, and operating means for said plate carried by said housing.

3. A parking meter comprising a housing having a coin slot, a coin guiding chute in said housing extending downwardly from said slot, said housing having a window between the ends of said chute, a plate pivotally carried by said housing, a coin holding lug carried by said plate and projecting into said slot for holding a coin above said window, a second coin holding lug carried by said plate disposed below said window and positioned laterally of said first lug, said second lug being disposed in released position when said first lug is in operative position and adapted to be disposed in operative position within said chute when said first lug is in released position, a pair of parallel lugs extending from said plate, a plate operating arm engaging between said pair of lugs, and key operated means connected with said arm for swinging the latter.
